Nelson M. Howard

UNITED STATES PATENT OFFICE.

KARL ENGEL, OF ARLINGTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LAST.

1,306,108.

Specification of Letters Patent. Patented June 10, 1919.

Original application filed December 2, 1914, Serial No. 875,126. Divided and this application filed October 13, 1917. Serial No. 196,360.

To all whom it may concern:

Be it known that I, KARL ENGEL, a citizen of the United States, residing at Arlington, in the county of Middlesex and State of 5 Massachusetts, have invented certain Improvements in Lasts, of which the following description, in connection with the accompanying drawings, is a specification, like reference characters on the drawings indicating like parts in the several figures.

This invention relates to lasts and is herein set forth with especial reference to its application to the manufacture of welt shoes made in accordance with the method described and claimed in my application Ser. 15 No. 875,126, filed Dec. 2, 1914, entitled Methods of making shoes, of which this application is a division, although it is not intended to limit this invention thereby.

20 A principal feature of the invention is a last having a clenching plate offset or separable from its tread surface over an area extending over more than half the length of the last. This structure facilitates the insertion of an insole member between the plate and the last bottom, as will be explained. In the last shown the plate is offset from the last bottom over an area extending along the margin of the last bottom 25 from about the heel breast to a point just back of the toe tip.

Another feature of the invention is a last having a clenching plate secured to it at the heel end only, being separable from the tread 30 surface of the last at other points, in order to permit the insertion of an insole member between the plate and the last bottom, for a purpose which will be explained.

Another feature of the invention is a last 35 having a clenching plate attached to the last only at the heel end and terminating short of the toe, and a supplementary clenching plate secured to the toe beyond the end of the former plate.

40 These and other features of the invention will be best understood from the following description of a preferred embodiment thereof, selected for purposes of illustration and

shown in the accompanying drawings, in which—

50 Figure 1 is a perspective view of the last.

Fig. 2 shows the insole used in practising the novel process referred to, and

Fig. 3 further illustrates the novel process.

The last 12 has a lift 21 which may, if 55 desired, be formed integrally with its wooden portion, as shown. The clenching plate 13 is fastened to this lift by the fastenings 16. The plate 13 is shaped like an ordinary clenching plate used on a McKay last but is fastened to the last only at the heel, as shown, and terminates short of the toe of the last. A supplementary clenching plate 18 is fastened to the toe of the last by 60 the fastenings 19. This plate is overlapped slightly by the plate 13. The lift 21 separates the plate 13 from the last and permits the insertion of an insole member as will be described.

The use of the last in practising the novel 70 welt shoe method of the parent application will now be briefly described.

The shoe upper 2 is cut substantially to its final outlines or to such size that the lower edge of the upper along the shank and at the forepart will terminate substantially at the last edge, thereby effecting an economy in cutting the upper leather. The toe and heel portions of this upper together 75 with the toe and heel stiffeners are then molded, preferably by the processes described respectively in my United States Letters Patent Nos. 947,895 and 1,001,745, to the shapes which these parts assume in the finished shoe. In order to provide sufficient material to enable the upper to be lasted over upon the insole and also for securing it to the insole, a narrow strip of 80 strong canvas 3 may be attached to the lower edge of the molded upper through the shank and about the forepart; or a lining, if present, may be extended beyond, and fastened to, the edge of the upper. This canvas strip 3 is shown secured by stitches 5 to the inner face of the molded upper 2 along its lower 85 edge so that it projects a considerable dis-

90

95

tance beyond said edge and a welt 6 is also secured preferably by the same stitches 5 along the lower edge of the molded upper 2 upon the outside thereof.

- 5 The insole to which the molded upper 2 is secured comprises preferably a main portion 8 of canvas or similar material to which the upper is secured, and a shorter flap 9 which may be of leather attached to the main 10 portion at the toe end only thereof by cement or other suitable means and terminating approximately at the forward edge of the heel seat, although an insole of leather having a split extending from the forward 15 edge of the heel seat toward the toe thereof and terminating short of the toe end, or an insole of other suitable material may also be employed.

The insole is placed upon the last with the 20 flap 9 interposed between the offset unattached portion of the plate 13 and the bottom face of the last and with the main portion 8 covering the entire bottom face of the last. The prepared upper is then assembled 25 on the last and lasted over on to the insole 8 with the aid of the lasting strip 3 and the marginal edge of the upper at the heel, and the extension strip 3 is then secured in lasted position by tacks 20 driven into the insole. 30 The tacks which are driven to secure the upper to the insole at the shank and forepart pass through the main portion 8 of the insole and are clenched thereon against the plate 13, and the tacks securing the heel and 35 extreme toe portions of the upper are clenched on the inner surface of the compound insole. The succeeding operations upon the shoe including the attachment of an outsole to the welt 6 are performed in 40 the usual manner.

After the last 12 is withdrawn from the shoe, the flap or slip sole 9 is cemented to the main portion 8, thus covering the lasting tacks 20 in the shank and forepart of the 45 shoe. A heel seat filler is located in the shoe at the heel and to cover up the heel nails and thus form a continuous smooth surface on the interior of the shoe upon which the foot of the wearer bears.

50 The advantages inherent in the novel process described and in the shoe produced by it are explained fully in my parent ap-

plication above referred to and need not be discussed in this application.

Having described my invention, what I 55 claim as new and desire to secure by Letters Patent of the United States is:—

1. A last having a clenching plate separated from its tread surface over an area extending over more than half the length 60 of the last.

2. A last having a clenching plate offset from the last over an area extending from the neighborhood of the heel breast to a point short of the toe tip.

3. A last having a clenching plate offset from the margin of its tread face from the neighborhood of the heel breast to the toe.

4. A last having a clenching plate secured to it at the heel end only, being unconnected with the tread surface of the last at other points so that an insole member may be inserted between the plate and the last bottom.

5. A last having a clenching plate attached to it only at the heel end and terminating short of the toe, and a supplementary clenching plate attached to the toe.

6. A last having a two-piece clenching plate offset from the tread face over an area extending more than half the length of the last.

7. A last having a two-piece clenching plate, each piece being attached only at an extremity of the last in such manner that an insole member may be placed between the plate and the last over substantially the entire shank and forepart portions.

8. A last having a clenching plate secured to the heel portion thereof, said plate being shaped to the contour of the bottom face of the last and terminating short of the toe end of the last, and an additional clenching plate secured to that portion of the bottom face of the last extending beyond the forward edge of said first-mentioned plate.

9. A last having a solid body and a two-piece clenching plate, each end of the last carrying a piece of the plate, and each piece being attached only at the extremity of the 100 last.

In testimony whereof I have signed my name to this specification.

KARL ENGEL.
